UNITED STATES PATENT OFFICE.

ISAAC OLSON, OF BELLINGHAM, WASHINGTON.

LOAD-BINDER.

No. 892,078.

Specification of Letters Patent.

Patented June 30, 1908.

Application filed January 13, 1908. Serial No. 410,657.

To all whom it may concern:

Be it known that I, ISAAC OLSON, a citizen of the United States, residing at Bellingham, in the county of Whatcom and State of Washington, have invented certain new and useful Improvements in Load-Binders, of which the following is a specification, reference being had to the accompanying drawings.

10 My invention relates to improvements in load binders for use upon log and lumber wagons and the like.

The object of the invention is to provide a device of this character which will be simple, 15 inexpensive, strong and durable in construction, which may be conveniently applied and operated and which when moved to its closed position will be self locking.

With the above and other objects in view 20 the invention consists in the novel construction and the combination and arrangement of parts hereinafter described and claimed, and illustrated in the accompanying drawings, in which

25 Figure 1 is a perspective view of the load binder in its open position; Fig. 2 is a side elevation of the same in its closed position; and Fig. 3 is a top plan view.

My improved load binder consists of an operating lever 1 and two hook-shaped links 2, 3. The lever 1 has at one of its ends a suitable handle 4 and adjacent to its other end is an enlarged portion 5 which is curved both longitudinally and laterally or transversely, 35 as more clearly shown in Figs. 2 and 3. The extremity 6 of said portion 5 of the lever is the part of the same that is laterally curved or offset and said extremity is substantially in longitudinal alinement with the body and handle portion of the lever, so that the central part of the longitudinally curved portion 5 is without the longitudinal axis of the lever, for a purpose presently explained. The hooks or links 2, 3 are arranged upon 40 opposite sides of the lever and both have their inner ends laterally curved or offset as at 7 to correspond to the lateral curve of the end 6 of the lever. The said end of the link 2 is pivoted upon a stud 8 projecting from one side of the extremity 6 of the lever and it is preferably retained upon said stud by a split pin 9 and a washer 10. The corresponding end of the other link 3 is similarly retained upon a pivot stud 11 projecting in an opposite direction from the central part of the curved portion 5 of the lever.

While the free ends of the links 2, 3 may be provided with any suitable means for engagement with the ends of the chain, cable or other binding element which surrounds the 60 load, I preferably provide them with the hooks 12, 13 as illustrated. These hooks 12, 13 are formed by bending the outer ends of the links upon themselves laterally in the plane of the offset inner ends of said links, as 65 more clearly shown in Fig. 3, in order that the line of draft or strain may be in substantially the same longitudinal plane. The offset ends of the lever and links, also shown more clearly in Fig. 3, tends to further 70 straighten the line of draft, as will be readily understood. In order to more effectively lock the parts in their stretched position and to relieve the pivot studs of strain I preferably provide upon one side of the lever a lip or 75 projection 14 which is adapted to take over the link 2, as shown in Figs. 2 and 3.

In use, the chain or other tie is passed around the load and its ends are engaged with the hooks 12, 13 when the parts of the 80 device are in their open position, as shown in Fig. 1. The lever 1 is then swung to the left so that the lip or projection 14 receives the link 2 between it and the lever. Owing to the shape of the inner end of the lever and to 85 the arrangement of the pivots 8, 11; it will be seen that when said lever is swung to its closed position both pivots will pass the center of the line of strain upon the links or hooks so that the device will lock itself in its 90 closed position.

It will be noted that the device is exceedingly simple and inexpensive in construction, that it is strong and durable in use and that it is exceedingly quick and convenient in 95 operation.

Having thus described my invention what I claim is:

1. A load binder, comprising a lever having one end laterally offset and a longitudinally curved portion adjacent to said end, links arranged on opposite sides of the lever and having laterally offset ends to correspond with the offset end of the lever, one link being pivoted upon one side of the curved portion of the lever and the other link being pivoted upon the other side of the offset end of the same, the outer ends of said links being bent upon themselves laterally into the plane of their offset inner ends to provide hooks, substantially as and for the purpose specified.
2. A load binder comprising a lever having

a longitudinally curved portion adjacent to one end, links arranged upon the opposite sides of the lever, one being pivoted to its curved portion and the other to its adjacent 5 end, and a lip or projection upon the lever adapted to engage one of the links, substantially as described.

3. The herein described load binder comprising a lever having a longitudinally curved portion adjacent to one end, pivot studs projecting from the opposite faces of the lever, one stud being adjacent to one end of the lever and the other upon the curved portion of the same, links disposed upon opposite sides 15 of the lever and engaged with said pivot

studs, means for retaining the links upon said studs, the inner or pivoted ends of the links and the adjacent end of the lever being laterally offset and the outer ends of said links being bent laterally to provide hooks disposed in the planes of the inner ends of said links, and a lip or projection upon the lever adapted to engage one of said links, substantially as set forth.

In testimony whereof I hereunto affix my 25 signature in the presence of two witnesses.

ISAAC OLSON.
